James L. Norris.

UNITED STATES PATENT OFFICE.

DANIEL JONES, OF BOSTON, MASSACHUSETTS.

SUCKER-ROD.

SPECIFICATION forming part of Letters Patent No. 273,234, dated February 27, 1883.

Application filed September 1, 1882. (No model.)

To all whom it may concern:

Be it known that I, DANIEL JONES, of Boston, in the county of Suffolk and State of Massachusetts, have invented an Improvement in 5 Sucker-Rods; and I do hereby declare the following to be a full and correct description of the same.

This invention relates to an improvement on the sucker-rod joint secured to me by Letters 10 Patent of the United States No. 119,232, September 26, 1871. As constructed under said Letters Patent, a series of annular and longitudinal channels are formed both in the rod and in the inner wall of the socket, and molten 15 metal run into said recesses after the rod has been driven into the socket. Under such construction the socket is required to be of considerable thickness, so as to admit of the channels being formed therein. It is extremely 20 desirable, however, to provide a thin, light, and at the same time a strong socket, for the reason that sucker-rods, which work within the limited space afforded by the small-sized tubing used for wells, should have the diameter 25 of the wooden rod decreased as little as possible by reason of the joint, and also, as rods of great length are employed, both strength and lightness are extremely desirable. To such end I provide the interior of the socket with 30 isolated longitudinally-arranged projections, which are made in the shape of triangular prisms, whereby a rod having a diameter corresponding to the bore of the socket can be driven in the same, the said projections cutting 35 in the wood so as to allow the rod to be inserted in the socket. The rod is provided with one or more annular grooves, and the socket-piece is provided with openings through which molten metal can be poured so as to fill the spaces 40 between the socket and the grooved portion or portions of the rod, as hereinafter more fully described, and illustrated in the annexed drawings, in which—

Figure 1 is a perspective view of the socket 45 with a portion broken away, so as to show the prismatic projections. Fig. 2 represents a portion of the rod. Fig. 3 is a section taken transversely through the socket. Fig. 4 is a longitudinal section through the rod and socket 50 fitted together.

Referring by letter to the drawings, A indi-

cates the rod, and B the socket. The rod is formed with one or more angular grooves or recesses, C, which extend around the rod. The tubular metal socket B is provided upon its 55 interior with one or more annular series of isolated projections, D, which are in the nature of triangular prisms arranged longitudinally within the socket. The tube or socket is screw-threaded at one end for the purpose of 60 coupling it with the socket of the next rod, and it is further provided with openings E, through which molten metal can be poured after the rod has been fitted in the socket. It will be seen that these wedge-shaped or triangular 65 prismatical projections D have each a sharp cutting-edge, d, formed longitudinally in the tube and at an angle to the wall thereof, said cutting-edge commencing at the wall and running toward the center of the tube until it terminates at a sharp point formed by the base or flattened end d' of the projection. It will also be observed that the socket is not required to be made thick in order that it may be recessed to form these projections, but that it is made of 70 equal thickness throughout, it being of course understood that the projections themselves constitute thickened portions at isolated points. The rod, having a diameter equal to that of the base of the bore of the socket, is fitted in 75 the latter by driving the socket upon the rod until the projections in the socket are at the upper portions of the inclined bed of the recesses in the rod whereby a space is left between the square end or bases of the prismatic 80 projections and the shoulder formed by the annular recess in the rod. As the socket is driven on the rod, the sharp edges of the projections cut their way into the rod, and by thus imbedding themselves in the rod insure a 85 strong connection between the rod and socket. Molten metal or some possible alloy which will expand in cooling is now run through the openings in the socket into the recess or recesses, thereby filling up the latter and leaving no space between the shoulder of the recess and the bases of the triangular prismatic 90 projections and binding the rod and socket firmly together. The form of these projections admits of their readily forcing their way 95 through the wood, and after the socket has been driven upon the rod the base portions of

said projections constitute abutments for the metal filling.

Having thus described my invention, what I claim is—

5 1. In a sucker-rod joint, the tubular metal socket provided with internal isolated wedge-shaped projections having cutting-edges, whereby when the said socket is driven upon the rod the projections force their way through the wood, substantially as described.

10 2. In a sucker-rod joint, the perforated tubular socket provided with wedge-shaped or triangular prismatic projections, substantially as described.

15 3. In a sucker-rod joint, the perforated tubular socket provided with internal isolated wedge-shaped or prismatic projections ar-

ranged on one or more annular sets, substantially as described.

4. The combination, with a sucker-rod recessed substantially as described, of the tubular metal socket provided with internal isolated wedge-shaped or triangular prismatic projections adapted to force their way through the wood when the socket is driven down 25 upon the rod, substantially as described.

The above specification of my said invention signed and witnessed at Boston this 30th day of August, A. D. 1882.

DANIEL JONES. [L. S.]
